WALL STRUCTURE AND BUILDING BLOCK THEREFOR

Morton M. Rosenfeld, Mount Vernon, N.Y.
(271 Madison Ave., New York, N.Y.)
Filed Mar. 9, 1962, Ser. No. 178,714
4 Claims. (Cl. 52—561)

The present invention is a continuation-in-part of my copending application Ser. No. 166,813, filed on Jan. 17, 1962, and entitled Wall and Block Therefor.

This invention relates to a wall structure and a building block therefor. More particularly, the present invention is directed to a wall formed from a plurality of superimposed courses of blocks with a layer of mortar therebetween and a novel block from which the wall may be constructed.

The wall and block therefor as set forth in my copending application adequately performs its intended function. However, the wall disclosed in my above mentioned copending application suffers from a disadvantage in that it does not present a smooth exterior surface on the wall so as to preclude detection of the fact that it is internally reinforced.

The wall structure of the present invention is preferably made from a double thickness of blocks which are structurally interrelated in a manner so that they may be superimposed over each other in the various courses. By providing a wall structure having superimposed overlapping blocks, it will be obvious that a stronger wall is provided. The primary purpose of the wall structure of the present invention is provided an internally reinforced wall by assembling blocks and with respect to previously anchored upright reinforcement rods.

It is an object of the present invention to provide a novel reinforced wall structure.

It is another object of the present invention to provide a novel wall structurally interrelated in a manner so that it may withstand higher pressures.

It is another object of the present invention to provide a novel building block.

It is another object of the present invention to provide a wall which is much stronger than those proposed heretofore, and yet is capable of being rapidly constructed by a novice.

It is still another object of the present invention to provide a novel wall which may be rapidly constructed from blocks which are identical with blocks thereabove and therebelow and with a particular orientation between the courses.

It is still another object of the present invention to provide a wall comprised of superimposed overlapping courses of blocks with all the blocks in one course being particularly orientated with respect to blocks in the courses thereabove and therebelow.

It is still another object of the present invention to provide a novel wall having a thickness twice that of the building blocks from which it is constructed, and internally reinforced in a novel manner.

Other objects will appear hereinafter.

For the purpose of illustrating the invention there is shown in the drawings forms which are presently preferred; it being understood, however, that this invention is not limited to the precise arrangements and instrumentalities shown.

FIGURE 1 is a partial perspective view of a wall constructed in accordance with the present invention.

FIGURE 2 is a plan view of the blocks in the first course of the wall illustrated in FIGURE 1.

FIGURE 3 is a plan view of the blocks in the second course of the wall illustrated in FIGURE 1.

2

FIGURE 4 is a perspective view of a typical block utilized in the construction of the wall illustrated in FIGURE 1.

Referring to the drawing in detail, wherein like numerals indicate like elements, there is shown in FIGURE 1 a wall designated generally as 10.

The wall 10 will be constructed of a plurality of overlapping courses. For purposes of the present discussion, wall 10 is illustrated as having a first course 12 and a second course 14 with mortar 16 disposed therebetween. It will be noted that the wall 10 has a thickness corresponding to twice the width of the building blocks from which it is constructed. As will be made clear hereinafter, the wall 10 is internally reinforced.

As shown more clearly in FIGURE 2, the first course 12 may include an end block 18. The end block 18 may be rectangular with side edges of the same length and end edges of the same length. The wall 10 is preferably provided with a width which is twice the width of the blocks 20-27. The blocks 20, 22, 24, and 26 are in a row. Blocks 21, 23, 25 and 27 are in a second row juxtaposed to the first row. It will be noted that the length of the block 18 is twice the width of the blocks 20-27 and thereby corresponds with the width of the wall 10.

Each of the blocks 20-27 are identical. Each of the blocks 20-27 is provided with a notch 28 at one end thereof. The width and length of the notch 28 is substantially equal to one-half the width of the blocks 20-27. As shown more clearly in FIGURE 4, each of the blocks 30 will have an end face 32 corresponding to one-half the width of the block and an end face 34 which corresponds to the full width of the block. Before constructing the first course 12, a plurality of upright rods 30 will be anchored to the supporting surface in a staggered pattern as illustrated more clearly in FIGURE 2. When the blocks 20-27 are positioned, it will be noted that the blocks in the first row are positioned so that their notch 28 is internal of the wall 10. Likewise, the blocks in the second row are positioned so that their notch 28 is internal of the wall 10.

When the blocks 20-27 are positioned, they have a particular relationship with respect to the staggered pattern of rods 30. Hence, it will be noted that a rod 30 is disposed within each of the notches 28 adjacent the smaller end face of each of the blocks 20-27.

When the first course 12 has been positioned as illustrated in FIGURE 2, a layer of mortar 16 will be provided across the top surface thereof. Sufficient mortar will be provided so that the area of the notches 28 will be completely filled with mortar. Thereafter, the second course 14 will be constructed. The second course 14 includes an end block 36 which differs from the end block 18. The end block 36 is provided with a corner notch 38 thereby causing the end block 36 to be P-shaped. One edge of the notch 38 has a length corresponding to the width of the blocks 20'-27'. The other edge of the notch 38 has a length corresponding to one and one-half times the length of the notches 28.

When the block 20' is positioned, its end face 34' will be juxtaposed to the shorter side edge of the block 36. The position of the block 20' automatically results in the rod 30 disposed within the notch 28' on the block 20' to be remote from the smaller end face of the block 20'. Accordingly, the blocks 20 and 20' will be staggered with respect to each other. A corresponding relationship will exist between the blocks 21 and 21', blocks 22 and 22', etc. Since the blocks of course 12 will be overlapped by corresponding blocks in the course 14, the wall 10 will be stronger than a wall constructed with blocks which are merely superimposed over one another in the adjacent courses. It will be noted that the notches 28' on the blocks 20' and 23' overlap each other in a central por-

tion of the wall 10. Mortar will be provided within the notches 28' in the second course 14. Except for the end blocks in the various courses, the wall 10 is constructed of blocks which are identical with each other. Since the notches on the blocks will be internal of the wall 10, it will be not be possible to detect that the wall 10 is internally reinforced. It will be noted that the disposition of the notches 28 and 28' enables the blocks 20-27 and 20'-27' to be inserted from a direction perpendicular to the plane containing the rods 30.

Hereinafter, the P-shaped block 36 may be referred to as a P-shaped starter block. Hereinafter, the rods 30 may be referred to as a staggered row of upright reinforcement rods. Hereinafter, the notches 28 or 28' may be referred to as a corner notch juxtaposed to the plane between each of the rows of blocks in each course.

The present invention may be embodied in other specific forms without departing from the spirit or essential attributes thereof and, accordingly, reference should be made to the appended claims, rather than to the foregoing specification as indicating the scope of the invention.

I claim:

1. A solid masonry wall structure comprising a plurality of alternate first and second courses of blocks superimposed over each other with a desired overlap, each course having two rows of blocks abutting at a medium plane of said wall with each row being completely on one side of said plane, a rectangular starter block for each of said first courses, said rectangular block having a length equal to the width of said wall, an L-shaped starter block for each of said second courses, both said starter blocks being of equal length with said L-shaped block having a width greater than said rectangular block by an amount equal to said overlap, said L-shaped block providing an open indented corner having dimensions of one half said length and double said overlap, said starter blocks being set with said length transversely across said plane, each of said blocks of said rows being of substantially solid rectangular shape of a width equal to one half said length of said starter blocks, said rectangular shape having a notch at one corner of dimensions equal to one half said

10
15

width of said shape, said overlap being less than said notch dimensions, said blocks of rectangular form being set in said rows with each notch thereof juxtaposed to said medium plane at the interior of said wall, and pairs of spaced upright reinforcement rods, each pair having a rod at each side of said medium plane and at each side of a plane tangent to each rod of said pair and perpendicular to said medium plane, each of said rods being in a notch and abutting against an adjacent block of said first courses and each of said rods being in a corner of a notch in said second courses.

2. A wall structure in accordance with claim 1 wherein said rectangular starter block has a width of one half said length and said rectangular shape is of a length equal to twice its width.

3. A wall structure in accordance with claim 1 wherein said second courses of blocks are set with notches of one row of blocks being coextensive with notches of the abutting row of blocks.

4. A wall structure in accordance with claim 1 wherein each rod is juxtaposed to a small end face of each block in said first courses, and each rod being remote from a small end face of each block in said second courses.
